(54) **SAW MILLS**

(76) Inventor: **Moses Coates**

Moses Coates, of Pennsylvania.

Letters Pat. No. Dated April 1, 1829.

The Schedule referred to in these Letters Patent, and making part of the same, containing a description in the words of the said Moses Coates himself of his improvement, In a Saw Mill.

specification. This machine is put in motion by an arm extending from a shaft to the saw gate commanding three hands, one of which acts upon a small half circular rag attached to another shaft or roller; on this shaft there are two straps which command the other two hands in such manner that they are brought to act upon a Retractile Log, which is secured to the common rag wheel; the first of those hands is suspended by a strap held to the end of a lever; at the point of time when it shall be required that the log retreat from the saw this lever is put in motion by a slider attached to the other end playing in a joint, and extending in perpendicular direction down to the carriage, where it is elevated by a trigger. The hands that act in the ordinary way for feeding the saw are commanded by the motion of the above said roller, being otherwise furnished with straps attached thereto and for the purpose of accelerating the motion of this roller, there is a prisionerating principle suitably applied. The log is thus brought to retrograde motion. For the purpose of setting the log to the required distance, there is a slider with a rag iron on the top, a pendant at the bottom, and a friction wheel playing in an open ended mortice, this slider passes through one of the main Posts and by one of the fender Posts. It is brought forward by an oblique elect catching the pendant; this elect is held fast by a screw to the sliding ring on the main head Block; the same kind of means are used for moving the stamp end of the log which is accommodated with a sliding head block. The friction wheels are so stationed as to move the log at the point of time when the saw is relieved. Thus in succession the log continues to be moved until the gauge relieves the lever which commands the water gate and the Mill is stopped.

Hilness.
